UNITED STATES PATENT OFFICE.

WILLIAM HERBERT ROYSTONE, OF NEW YORK, N. Y.

TOILET ARTICLE.

1,425,138.

Specification of Letters Patent. Patented Aug. 8, 1922.

Application filed December 8, 1921. Serial No. 520,793.

To all whom it may concern:

Be it known that I, WILLIAM HERBERT ROYSTONE, a citizen of the United States, residing at New York city, county and State 5 of New York, have invented new and useful Improvements in Toilet Articles, of which the following is a specification.

This invention relates to an improved toilet article and more particularly to a 10 toilet article which may be provided with two compacts of face powder, rouge or the like, there being preferably provided a rouge compact and a face powder compact.

The objects of the invention are the provision of an improved toilet article whereby 15 there may be provided a rouge compact and a powder compact each associated with a puff or applicator, so that the user may obtain rouge or powder at will; the whole being so assembled as to occupy a minimum space.

Another object is to provide a toilet article wherein the new compacts may be readily positioned and wherein worn out compacts may be easily replaced.

In the accompanying drawings I have shown, for purposes of illustration, one of the many possible embodiments in which 25 my invention may take form. In these drawings, Fig. 1 is an elevational view of the toilet article:

Fig. 2 is a section on the line 2—2 of Fig. 1; and

Fig. 3 is an elevation showing the covers opened.

A ring or sleeve 5 of a length approximately equal to the thickness of two new compacts is provided with covers 6 and 7 hingedly connected at 8 and 9. The ring may be circular, as shown in the drawings, 35 when the inside diameter will be equal to the outside diameter of the compact. Where, however, it is desired to use non-circular compacts, an appropriate shape is given to the ring whereby it may surround 40 and support the periphery of the compacts. Each cover is adapted to be closed down upon the adjacent end of the sleeve or ring 5. The ring 5 is preferably provided with two beads 10 and 11 to limit the closing 45 movement of the covers 6 and 7. The ring is also provided on the side opposite the hinges 8 and 9 with projections 12 and 13 which are adapted to cooperate with recesses 14 and 15 in the cover members 6 and 55 7 so as to hold the covers in closed posi-

tion. The inside of each cover is provided with a mirror 16 which may be held in place by a ring 17.

The metal parts of the toilet article above described may be made of any suitable stiff 60 metal, plated and ornamented as desired.

The reference characters 18 and 19 indicate two compacts of face powder, rouge or the like, preferably one of these compacts being rouge, the other being face powder. 65 Each of these compacts is preferably made of compressed powder enclosed in previous cloth, and backed up by a sheet of cardboard, or the like, such as is described in my Patent No. 1,388,204 of August 23, 1921. Cloth 70 covered compacts cooperate especially well with the sleeve 5 for the reason that the compact, when forced inside the same, is held by friction between the cloth and the inner surface of the sleeve or ring. The 75 friction between the parts however is not very great, as one can easily replace the compacts when worn out or substitute new compacts.

Powder puffs 20 and 21, one for each compact, are located intermediate the mirrors and the compacts, so that a puff carrying the desired tint is always available for service.

It is apparent that the toilet article is 85 one which will be found convenient in use. The user may open the desired cover and obtain a supply of the selected toilet preparation. The compacts may slide in the annular frame to a slight extent when rubbed 90 by the puff but this causes no harm.

It will be noted that the article may be made of the minimum amount of material and is also very thin, owing to the economical use of material and absence of 95 unused space.

What is claimed is:

1. In a toilet article, a frame for carrying two compacts of face powder, rouge or the like, back-to-back in abutting relation, said 100 frame comprising a ring or sleeve cooperable with the compacts to surround and support the periphery thereof, and a cover for each end of the ring or sleeve.

2. In a toilet article, a frame for carrying two compacts of face powder, rouge or the like, back-to-back in abutting relation, said frame comprising a ring or sleeve cooperable with the compacts to surround and support the periphery thereof, a cover for 110

each end of the ring or sleeve, and hinges and catches for releasably holding the covers in place.

3. In a toilet article, a frame for carrying two compacts of face powder, rouge or the like, back-to-back in abutting relation, said frame comprising a ring or sleeve coop-

erable with the compacts to surround and support the periphery thereof, a cover for each end of the ring or sleeve, hinges and 10 catches for releasably holding the covers in place, and a mirror carried by each cover on the inside thereof.

WILLIAM HERBERT ROYSTONE.
